(57) CLAIM

The ornamental design for a sweater pattern, as shown and described.

DESCRIPTION

FIG. 1 is a front view of a sweater pattern showing my new design;

FIG. 2 is an enlarged detailed view of the upper band of the sweater pattern of FIG. 1;

FIG. 3 is an enlarged detailed view of the lower band of the sweater pattern of FIG. 1;

FIG. 4 is an enlarged detailed view of the left arm band of the sweater pattern of FIG. 1; and,

FIG. 5 is an enlarged detailed view of the right arm band of the sweater pattern of FIG. 1.

The broken lines of FIGS. 1-5 illustrate environmental matter and form no part of the claimed design. The back side of the sweater pattern, which is not shown in the drawings, forms no part of the claimed design.

1 Claim, 3 Drawing Sheets

FIG. 1
